(57) **CLAIM**

The ornamental design for an assembly of magnifying lens for use with phones, cell phones and pagers, as shown and described.

DESCRIPTION

FIG. 1 is a front elevation view of an assembly of magnifying lens for use with phones, cell phones and pagers, showing my design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof; and,

FIG. 7 is a perspective view of the lens thereof.
